UNITED STATES PATENT OFFICE.

ALFRED J. JOHNSON, OF GRAND RAPIDS, MICHIGAN, ASSIGNOR TO J. W. YORK & SONS, OF GRAND RAPIDS, MICHIGAN.

SAXOPHONE.

Application filed January 3, 1925. Serial No. 363.

This invention relates to improvements in saxophones and similar instruments.

The objects of the invention are to provide a tone hole structure which will not leak, in which the use of an exposed solder joint is avoided, in which there is an effective baffle to prevent the escape of saliva through the tone hole to the pad, in which the outer surface of the tone hole is so formed that it has an effectively rounded and smooth contact surface, and in which there is a lining and facing to the tone hole socket of non-corrosive metal or non-corrosive material.

Objects pertaining to details will definitely appear from the detailed description to follow.

I accomplish the objects of the invention by the devices and means described in the following specification. The invention is defined and pointed out in the claims.

A structure which is a preferred embodiment of my invention is illustrated in the accompanying drawing, forming a part of this application, in which:

Fig. I is a detail view of the body or branch of a saxophone or similar wind instrument such as a flute or clarinet, with the tone hole structure in the process of manufacture.

Fig. II is a transverse detail sectional view taken on line 2—2 of Fig. I, showing the tone hole structure in the process of manufacture.

Fig. III is a similar sectional view showing the next step of the operation in which the wall of the body or branch is cut away by circular saw or boring tool.

Fig. IV is a detail sectional view showing the introduction of the non-corrosive metal lining and the disposition of the spinning tool in dotted lines for expanding and spinning the metal outwardly over the outer end of the tone hole socket to form the contact surface.

Fig. V is an enlarged detail sectional view showing the complete tone hole structure.

Fig. VI is a detached detail of the tubular socket for the tone hole.

Fig. VII is a detached detail view of the tubular lining blank flanged internally and ready to introduce into the socket.

In the drawing similar numerals of reference refer to similar parts throughout the several views and the sectional view is taken looking in the direction of the little arrows at the ends of the section line.

The parts of the drawing will be identified by their numerals of reference. 1 is the body

or branch of a saxophone or other similar instrument. 2 is the tubular shell socket or vertical wall around the tone hole. 3 is the light line of solder by which the same is united to the branch. The inner end of this socket is cut on the arc of a circle to conform to the side of the branch and the outer end is square across. When the socket is soldered in place it embraces a circular portion of the wall 4. This is cut away to form the opening 5 by the usual circular cutting saw 6,—see Fig. III where this step of the operation appears.

The non-corrosive metal lining 7 is tubular in form to conform to this socket, having an outwardly projecting flange 8 at its inner end 70 conformed to the inner surface of the branch or body at that point. The outer end 9 projects beyond the socket portion 2 in position to be acted upon by a spinning tool 10, indicated in dotted lines in Fig. IV. The tool 10 spins the projecting end of the non-corrosive metal lining 9 over into a close-engaging bead portion 11 accurately conformed to the outer end of the tubular socket 2. By this means it will be noted that the inner flange 8 forms 80 a baffle to prevent the flow of saliva to the tone hole and that the outer end of the metal, which is quite ductile and non-corrosive, is spun perfectly smooth so that it will not have a cutting or abrading effect on the valve pad. 85 The non-corrosive ductile metal is preferable for this purpose as it can be spun very effectively in place. However, such materials as celluloid or even hard rubber can be formed in place. The solder joint is only desirable as 90 a step in manufacture and the solder can be substantially all cleared away in finishing, as the lining holds the parts effectively together.

I desire to claim the invention specifically 95 and also broadly, as pointed out in the appended claims.

Having thus described my invention, what I claim as new and desire to secure by Letters Patent is:

1. In a saxophone or similar instrument, a tone hole structure comprising the combination with the body provided with a perforation at the side, of a tubular socket section secured to said body and surrounding said perforations and suitably soldered thereto, and a ductile non-corrosive metal lining member with an expanded projecting flange within the instrument and its outer end spun to conform to the socket section to retain the same 110

and form a smooth contact surface for the pad, as specified.

2. In a saxophone or similar instrument, a tone hole structure comprising the combination with the body provided with a perforation at the side, of a tubular socket section secured to said body and surrounding said perforations, and a ductile non-corrosive metal lining member with an expanded projecting flange within the instrument and its outer end spun to conform to the socket section to retain the same and form a smooth contact surface for the pad, as specified.

3. In a saxophone or similar instrument, a tone hole structure comprising the combination with the body provided with a perforation at the side, of a tubular socket section secured to said body and surrounding said perforations, and a non-corrosive lining member with an expanded projecting flange within the instrument and its outer end spun to conform to the socket section to retain the same and form a smooth contact surface for the pad, as specified.

25 4. In a saxophone or similar instrument, the combination with the body of a tone hole

structure formed by a tubular socket section, and a ductile non-corrosive metal lining member with an expanded projecting flange within the instrument and its outer end spun to conform to the socket section to retain the same and form a smooth contact surface for the pad, as specified.

5. In a saxophone or similar instrument, the combination with the body of a tone hole structure formed by a tubular socket section, and a ductile non-corrosive metal lining member with its outer end spun to conform to the socket section to retain the same and form a smooth contact surface for the pad, as specified.

6. In a saxophone or similar instrument, the combination with the body, of a tone hole structure formed by a tubular socket section, and a ductile non-corrosive metal lining member, with an expanded projecting flange forming a baffle guard for the tone hole within the instrument, as specified.

In witness whereof I have hereunto set my hand.

ALFRED J. JOHNSON.
